STOCK-FEEDING MECHANISM FOR
SWAGING MACHINES

Julius B. Tiedemann, Milwaukee, and Bertil G. Winstrom, Granville, Wis., assignors to A. O. Smith Corporation, Milwaukee, Wis., a corporation of New York

Application June 19, 1941, Serial No. 398,796

9 Claims. (Cl. 80—14)

This invention relates to stock feeding mechanism for swaging machines.

An object of the invention is to provide improved mechanism of this character for intermittently feeding and rotating tubular stock in synchronism with intermittently closing dies of the swaging machine.

A further object of the invention is to provide a device of this character in which bearings and other important parts are shielded against the heat radiated from hot tubular stock passing through it.

These and other objects of the invention will be clear from the following detailed description and the drawings in which:

Figure 1 is a top plan view of two feeding devices in schematic relation to the swaging machine;

Fig. 2 is a side elevation showing the drive for the feeding devices and the means for synchronizing them with the swaging machine;

Fig. 3 is a top plan view of the feeding mechanism on an enlarged scale;

Fig. 4 is an end elevation, partly in section on line 4—4 of Fig. 3, looking towards the left;

Fig. 5 is a vertical section on line 5—5 of Fig. 3; and

Fig. 6 is a sectional view on the line 6—6 of Fig. 4, partly broken away and with parts omitted.

The stock or pipe feeding mechanism comprises a housing 1 mounted on guides 2 so as to be free to slide back and forth longitudinally of pipe 3. Within the housing, a hollow shaft 4 unites the two end members 5 and 6 which are mounted to rotate on bearings 7 in the housing. Oil seals 8 are provided between the housing and the two end members to retain lubricating oil within the housing. The shaft 4 and end members 5 and 6 are rigidly secured together and are rotated as a unit by shaft 9 driving through gear 10, idler gear 11, and gear 12 fastened to the shaft 4.

Rigidly secured to the end member 5 and rotating with it, two tubes 13 and 14 are provided with heat insulating material 15 to shield the mechanism from heat radiated by the hot pipes passing through it. Despite this shield, however, some heat is naturally transferred to the shaft 4 and end members 5 and 6. For this reason the end members are mounted to rotate externally on the bearings 7 in the housing 1 so that the expansion caused by heating will increase rather than decrease the clearance between the bearing and the part rotating

around it. If the shaft 4 were mounted to rotate inside bearings in the housing, expansion due to heating of the shaft by the pipes passing through it might cause the shaft to bind in the bearings.

Lubricating oil is supplied to the bearings under pressure and passes from them into the housing where it is splashed around to lubricate the gears and other parts of the mechanism. The oil may be circulated at a sufficient rate to remove heat transmitted from the hot pipes and keep the mechanism cool.

Two shafts 16 are mounted in bearings 17 in end member 6. Two arms 18 are secured to each shaft inside the housing and carry between them at their free ends a cam roller 19. The cam rollers bear against a cam surface formed of two cams 20, each of which is supported on a cross head 22 movable between guides 23. Air cylinders 24 are mounted in trunnions 25 to act through levers 26 and cylindrical thrust block 27 to move the crossheads 22 and cams 20 towards or away from the center of the machine.

Externally of end members 6, each of the shafts 16 carries an arm 28. These arms are pressed apart by springs 29 which act to hold the cam rollers 19 pressed against cams 20. A jaw 30 for grasping the pipe is mounted on each arm 28. Springs 31 between the arms and jaws provide a resilient mounting for the jaws and insure the gripping of the pipe irrespective of the slight variations in dimensions inevitable in quantity production.

The swaging machine 32, with which the feeding mechanism is designed to operate, may comprise two intermittently operating dies 33, driven by any suitable mechanism. Two feeders will normally be used with each swaging machine, one to feed pipe to it, and one to remove pipe from it. The feeders are moved longitudinally of the pipe axis in synchronism with the swaging dies by means which are connected to the main drive for the swaging machine, and act 45 on the tie rods 34 connecting the two feeders.

To provide for the longitudinal movement of the feeding devices, each shaft 9 is splined within a driving sleeve 35 secured to the end of a shaft 36 rotated in synchronism with the swaging machine by gearing 37.

The operation of the feeding mechanism is as follows: When a new section of pipe is to be fed to the machine, air is applied to the air cylinders 24 to separate cams 20. The arms 28 are forced apart by springs 29 to keep the jaws 30 from

closing upon the pipe which can therefore be run rapidly into position by feed rolls not shown in the drawing. When the pipe nears the swaging machine, the air cylinders are used to force cams 20 together. As end member 6 rotates on its axis, the cam rollers 19 follow the cam surface and cause the jaws 30 to alternately open and close upon the pipe. In their closed position, the jaws grip the pipe between them, rotate it on its axis, and move it forward by virtue of the forward motion of the feeder. The feeder is synchronized with the swaging machine to make the feeding and turning of the pipe come at a time when it is not gripped between dies 33. Upon completion of the feeding stroke, the cam allows the cam rollers 19 and the jaws 30 to recede from the center line of the machine, thus releasing the pipe from the feeder in preparation for another stroke of dies 33. The pipe travels intermittently through the machine until it is all reduced in diameter.

The invention is claimed as follows:

1. A device of the class described comprising a housing, means to impart an axial reciprocating movement to the housing, constantly rotating mechanism within the housing with an axial opening for the passage of stock to be fed, jaws outside the housing carried by the rotating mechanism, means within the housing to cause the jaws to intermittently grip the stock in order to effect its rotation and forward feed, and means for making said last named means inoperative to provide for rapid insertion and removal of the stock from the device.

2. A device of the class described comprising constantly rotating mechanism with an axial opening therethrough for the passage of stock to be fed, a shield of heat insulating material within the opening, means for imparting an axial reciprocating movement to the mechanism, means on said rotating mechanism for intermittently gripping the stock to effect its rotation and forward feed, and means for making said gripping means inoperative to provide for rapid insertion and removal of stock.

3. In a device of the class described, a housing, constantly rotating mechanism within the housing with an axial opening therethrough for the passage of heated stock, and a bearing between the housing and rotating mechanism, said bearing having its internal member secured to the housing and its outer member secured to the rotating mechanism whereby expansion of the mechanism and outer member of the bearing by heat transmitted from the heated stock increases the clearance between the two members of the bearing.

4. In a device of the class described, a support, a rotatable mechanism with an axial opening therethrough for the passage of heated stock, and a bearing between the support and rotatable mechanism, said bearing having its internal member secured to the support and its external

member secured to the rotatable mechanism whereby expansion of the mechanism and external member of the bearing by heat transmitted from the heated stock increases the clearance between the two members of the bearing.

5. In a device of the class described with an external support and an internal rotatable mechanism exposed to radiant heat from bodies at high temperature, a bearing between the support and rotatable mechanism with the outer member of the bearing secured to the rotatable mechanism.

6. A pipe feeding device comprising a housing, a rotating member within the housing with an axial opening therethrough for the passage of pipe and an end section closing one end of the housing, a plurality of shafts parallel to the axis of the rotating member but displaced therefrom mounted in bearings in the end section and projecting inside and outside the housing, an arm secured to each shaft inside the housing, a cam roller carried by the arm, a second arm secured to each shaft outside the housing carrying a jaw to grip the pipe, means to normally spread the jaw apart, cam surfaces within the housing to bear against the cam rollers and force the jaws to close during a part of each revolution of the rotating member, and means to move the cam surfaces out of engagement with the cam rollers to permit the jaws to remain open throughout an entire revolution of the rotating member.

7. A device of the class described comprising a housing, means to impart an axial reciprocating movement to the housing, constantly rotating mechanism within the housing with an axial opening for the passage of stock to be fed, jaws outside the housing carried by the rotating mechanism, and means within the housing to cause the jaws to intermittently grip the stock in order to effect its rotation and forward feed.

8. A device of the class described comprising constantly rotating mechanism with an axial opening therethrough for the passage of stock to be fed, a shield of heat insulating material within the opening, means for imparting an axial reciprocating movement to the mechanism, and means on said rotating mechanism for intermittently gripping the stock to effect its rotation and forward feed.

9. A device of the class described comprising a constantly rotating member having an axial opening for receiving stock to be fed, therethrough, means operated by said member to intermittently grip the stock, mechanism rendering said means inoperative at will independently of the rotation of said member, and a housing for said rotating member to protect the same and to hold oil for the operating mechanism of said rotating member.
